UNITED STATES PATENT OFFICE.

MELVIN G. FARIS, OF THE UNITED STATES ARMY.

ANTIFREEZING DEVICE.

1,324,310.

Specification of Letters Patent.

Patented Dec. 9, 1919.

Application filed April 7, 1917. Serial No. 160,438.

To all whom it may concern:

Be it known that I, MELVIN G. FARIS, a citizen of the United States of America and in the Army of the United States of 5 America, have invented certain new and useful Improvements in Antifreezing Devices, of which the following is a full and clear specification.

The object of this invention is to provide 10 a simple automatic device for use in connection with motor vehicle radiators and other water circulating systems, whereby the system will be drained of its water immediately prior to the moment water in the system 15 reaches the freezing point, as more fully hereinafter set forth.

In the drawing—

Figure 1 is a vertical sectional view of 20 my device;

Fig. 2 is a side elevation of the expansion cylinder with the valve-cap removed;

Fig. 3 is a detail horizontal section on the line 3—3 of Fig. 1; and

Fig. 4 is a detail view of a portion of 25 the interior of the valve-cap showing the latch device.

Referring to the drawing annexed by reference characters, *a* designates a radiator of a motor vehicle or other circulating system, and *b* designates a pipe connected to the lowest part of said system and extending to the lower end of a small expansion cylinder *c* whose lower end is closed and whose upper end is open, the exterior of this cylinder being provided with a plurality of separated packing rings *d* to provide a watertight fit with a sliding valve-cap *e* fitted down over the cylinder.

Near the lower end of the cylinder *c*, at a 40 point between two of the packing rings, the cylinder is provided with one or more drain slits or openings *f*. At the point of freezing, the water in the cylinder *c* expands and thus lifts the valve-cap *e* far enough to uncover 45 drain ports *f*, whereby the radiator or other system *a* will be drained through said ports *f*. To hold the valve-cap up when thus lifted, I may provide any suitable means; the device shown consists of a spring catch 50 *g* fastened to the valve-cap *e* and normally bearing against a vertical series of ratchet teeth formed in the expansion cylinder *c* and facing upwardly.

It will be understood that in the most desirable embodiment of my invention, the cylinder *c* will have very small capacity as

compared with the radiator or other system and will be located a distance therefrom, so that the water in the expansion cylinder *c* will reach the freezing point before the 60 water in the system that is to be protected against freezing. Upon expansion of the water in the cylinder *c* due to the same reaching the freezing point, the valve-cap will be raised sufficiently to uncover the 65 drain ports *f*, the proportions of the parts being such that the increase in volume of the water would be sufficient to raise the cap the desired distance. As soon as the water starts to drain, it will cause a movement of the water throughout the radiator or other system and thus will prevent freezing during the operation of draining. When the cap is raised, the automatic catch *g* will hold it in its elevated position. It will be 70 understood, of course, that any other suitable locking device may be employed for holding the cap up when it is once raised.

This device being arranged at a point below the lowest water pocket of the radiator or system to be protected, it will be understood that the weight of the cap, together with the friction generated by the impingement against the packing rings and the pressure of the spring catch, must be 80 such as to resist the tendency of the upward pressure of the water to normally lift the cap. It will be observed also that in view of the fact that this drain device is located at a distance from the circulating system, there 85 will be little or no liability of the valve-cap being raised sufficiently to uncover the drain ports by the expansion under heat of the water, especially in view of the fact that the increase in volume of water due to heat- 90 ing it will be usually taken up in the radiator or the exhaust thereof. However, even if the water in the expansion cylinder *c* becomes as highly heated as the water in the radiator system, it will be an easy matter 95 to so proportion the parts that such expansion of the water will not uncover the drain ports, since water does not expand as much under heat as it does in the act of freezing.

The nature and scope of the invention having been thus indicated and its preferred embodiment having been specifically described, what is claimed as new is:

1. In a device of the class set forth, an open-top cylinder provided with a drain 110 port or ports and connected to a water receptacle or system to be protected, a cylin-

der fitted down over said cylinder adapted to close the upper end thereof and to normally close said drain, means being provided for holding said cap up off the port 5 when raised by expansion of water in the cylinder.

2. In a device of the class set forth, an open-top cylinder provided with a drain port near its lower end, a pipe connecting 10 the cylinder at a point below said port with

a system to be drained, a valve-cap fitted down over said cylinder, this cap normally closing the port and forming a closure for the upper open end of the cylinder, means being provided for locking the valve-cap 15 up when it is slid upwardly on the cylinder.

In testimony whereof I hereunto affix my signature.

MELVIN G. FARIS.
